UNITED STATES PATENT OFFICE.

JOHN BRENING, JR., OF McCOOK, NEBRASKA.

OIL-BURNER.

SPECIFICATION forming part of Letters Patent No. 772,496, dated October 18, 1904.

Application filed May 28, 1904. Serial No. 209,329. (No model.)

To all whom it may concern:

Be it known that I, JOHN BRENING, Jr., a citizen of the United States, residing at McCook, in the county of Redwillow and State 5 of Nebraska, have invented certain new and useful Improvements in Oil-Burners; and I do declare the following to be a full, clear, and exact description of the invention, such as will enable others skilled in the art to 10 which it appertains to make and use the same.

This invention relates to oil-burners of that type specially adapted for use in connection with steam-boilers and in which the fuel-oil employed is vaporized and injected with 15 steam into the fire-box of the furnace and there consumed to generate steam.

The object of the invention is to provide a burner of this character which is efficient for use on steam-boilers of different types and 20 which embodies certain improved features of construction and combinations of parts, as hereinafter described and claimed.

In the accompanying drawings, Figure 1 is a sectional view through a portion of a boiler 25 equipped with my invention. Fig. 2 is a sectional view through the burner on an enlarged scale, and Figs. 3, 4, and 5 are similar views of interchangeable injector - nozzles adapting the device for use in connection with 30 different types of boilers.

Referring now more particularly to the drawings, 1 represents the fire-box, and 2 the steam-dome of a boiler, 3 an oil-supply tank, and 4 my improved burner device for vaporizing oil fed from the tank 3 and discharging the same into the fire-box 1 to heat the boiler 35 for a production of steam.

The burner device 4 comprises in its construction a tubular body portion 5, having an 40 internally-threaded boss or pipe connection 6 at a point between its ends and receiving the threaded end of an oil-supply pipe 7, leading from the tank 3, said pipe being provided with a controlling-valve 8, whereby the flow 45 of oil to the burner may be regulated.

Extending longitudinally within and through the tubular body or casing 5 is a steam-nozzle 9, which is provided at one end with a tapering point 10 to eject the steam in 50 a jet to commingle with the oil and spray it

into the fire-box 1. The opposite end of the nozzle 9 is externally screw-threaded, as shown at 11, for connection with a coupling 12, connecting the same with one end of a steam-supply pipe 13, leading from the steam-dome 55 2 of the boiler.

The outer end of the body or casing 5 of the burner is provided with internal screw-threads 14 for connection with a coupling 15, which has a threaded portion 16 to engage 60 the threads 14, an outer sleeve 17, and an intermediate polygonal portion 18, the latter projecting beyond said sleeve and adapted for the application of a wrench, by means of which the coupling may be conveniently connected to and disconnected from the body or casing 5. The inner face of the polygonal portion may be provided with a suitable groove or recess to receive a packing 19 to 65 form a steam and fluid pipe connection. 70

Working on the screw-threads 11 of the outer end of the steam-nozzle 9 is a nut 20, which has a tubular projection 21 extending into the sleeve 17 of the coupling and is formed with a groove 22 to receive pins or screws 75 23, which connect said nut with the coupling, and yet permit it to turn thereon. The nut may be rotated in either direction by a hand-wheel or other suitable form of grip 24, as will be readily understood. The movement 80 of this hand-wheel in one direction or the other will adjust the nozzle 9 longitudinally to regulate the jet action of the tip 10.

The inner end of the tubular body or casing 5 is provided with internal screw-threads 26 to 85 receive a coupling upon the end of an injector-nozzle of suitable construction. In the drawings I have shown three different forms of interchangeable nozzles which adapt the device for use upon different types of boilers and 90 boilers of different capacities. The nozzle 26 (shown in Figs. 1, 2, and 3) is designed for small boilers and ordinary stationary boilers and comprises a tapering body portion 27, having at its inner end a screw-threaded coupling 28 to engage the said threads 25 and provided at a point in advance of said coupling with a polygonal portion 29 to adapt it to be conveniently applied and removed. In the construction shown in Fig. 5 the nozzle 26' is 95 100

detachably fitted upon the end of an independent coupling-pipe 30, which is provided with a threaded end 28 and polygonal portion 29, similar to the corresponding parts of the nozzle 26. The detachable connection in this case is made by forming the nozzle with a cylindrical end 31, fitting upon a reduced portion 32 of the coupling and secured thereto by screws or like fastening devices 33; but any other desired form of connection may be employed. The nozzle 26' further differs from the nozzle 26 in form and size, being made of frusto-conical shape or bell shape to project the hydrocarbon vapor and flames over a greater area in the fire-box of the boiler. This type of nozzle is especially adapted for use in connection with boilers having ordinary straight flues. The nozzle 26^a and coupling shown in Fig. 5 correspond to those shown in Fig. 4, except that the nozzle is disk-shaped and has a greater flare to project the vapor and flames over a still wider area. This construction is employed when the burner is applied to boilers of the return-flue type, thus preventing a back action of the products of combustion.

In the operation of the device the controlling-valves in the oil and steam pipes are opened, and the oil flows through the pipes 30 into the casing 5 and is drawn upward into the injector-nozzle by the suction produced by the steam escaping from the tip 10 of the steam-nozzle 9, the jet of steam escaping from the tip 10 further causing the oil to be projected into the fire-box 1 in the form of spray, which being thereby commingled with the steam is placed in condition for complete combustion. By adjusting the hand-wheel the steam-nozzle 9 may be moved longitudinally 35 to set the tip 10 at different points with relation to the nozzle 26, thus regulating the effect of the blast and the suction action of the oil.

From the foregoing description, taken in

connection with the accompanying drawings, 45 the construction and operation of the invention will be readily understood without requiring a more extended explanation.

Various changes in the form, proportion, and the minor details of construction may be 50 resorted to without departing from the principle or sacrificing any of the advantages of this invention.

Having thus described my invention, what I claim, and desire to secure by Letters Patent, is—

1. In an oil-burner, the combination with a casing provided at one end with a discharge-nozzle, of a source of oil-supply communicating with the casing, an adjustable steam-injector disposed within the casing and having a threaded surface, means for supplying steam thereto, a coupling upon the end of the casing opposite the nozzle, a nut engaging the steam-nozzle, and adjusting means connected 60 to the nut and revolubly connected with the coupling, substantially as described.

2. In an oil-burner, the combination with a casing provided at one end with a discharge-nozzle, of a source of oil-supply communicating with the casing, a steam-injector having a nozzle and disposed within the casing, said injector having a threaded surface, a sleeve on the casing, a hand-nut having a tubular portion entering the sleeve, a coupling connected to the sleeve and to the casing, and means whereby said hand-nut may be rotated independently of the coupling to adjust the injector relatively to the discharge-nozzle of the casing, substantially as described. 70

In testimony whereof I have hereunto set my hand in presence of two subscribing witnesses.

JOHN BRENING, JR.
